Inventor,

Harvey D. Geyer,

Donald S. Smith,

Attn: Attorney

UNITED STATES PATENT OFFICE.

HARVEY D. GEYER, OF DAYTON, OHIO, ASSIGNOR TO THE DAYTON STEEL RACQUET COMPANY, OF DAYTON, OHIO, A CORPORATION OF OHIO.

METHOD OF MAKING TENNIS-RACKET HANDLES.

Application filed May 6, 1922. Serial No. 559,050.

One of the principal objects of my invention is to provide a wood handle for tennis rackets, that is economical to produce and efficient in service.

5 It is another object of my invention to provide a new method of making these handles in quantity production, by first grooving two sections of wood and then gluing or otherwise securing them together to form 10 a handle containing groove-formed holes to receive the legs of a metal tennis racket frame, as opposed to the unsatisfactory method of making the handle in one piece and thereafter drilling or boring the leg-receiving holes therein.

15 My improved method not only insures economy in the manufacture of a tennis racket handle, but provides a handle which, when completed, may be quickly and securely applied to a metal tennis racket frame.

20 In the accompanying drawings, Figure 1 is a plan view of a metal tennis racket frame to the legs of which my improved handle is applied. Figure 2 is a plan view of one of 25 the grooved handle sections. Figure 3 is a side view of a handle after its sections have been glued together, showing a pin in one of its groove-formed holes. Figure 4 is a plan view of a clamp containing a plurality of 30 handles, showing pins in some of the holes therein. Figure 5 is a plan view of a wood section containing a single longitudinal 35 groove in its upper face. And Figure 6 is an end view of two wood sections, showing an alining bead in one and a groove in the other to receive it.

Throughout the specification and drawings, similar reference characters denote corresponding parts.

40 Referring to the accompanying drawings, the numeral 1 designates an elongated piece or section of wood of the desired length and width for a tennis racket handle. It is rectangular in cross section, and in its upper surface there is formed by a suitable machine, a pair of parallel longitudinal grooves 45 2, 2. Each of the latter is semi-circular in cross section, so that when two of the sections are glued or otherwise secured together, the grooves in one section will form with the grooves in the other section, holes 3 that are adapted to receive the legs 4, 4 of a metal tennis racket frame 5, whereby the completed handle may be firmly secured 50 to the latter.

My improved method of producing these tennis racket handles efficiently in quantities, consists, first, in sawing or cutting from wood, two sections 1, 1 of suitable size and shape for each handle to be made. Two 60 parallel, longitudinal grooves 2, 2 are then formed in the top side of each section 1 by a sticker or other machine. In Figure 5 I have illustrated a wood section 1 with but one groove 2, for cases in which the handle 65 is to be applied to a tennis racket frame having but one leg portion.

Glue or other adhesive is applied to the grooved sides of the handle sections 1, 1, after which they are firmly pressed together 70 in a clamp 6, with the grooves in one section opposite the grooves in the other section to form the leg-receiving holes 3. Pins 7 are then driven into the holes 3 to bring 75 them into exact relation to each other and the outer surface of the handles. These pins are preferably heated before being inserted in the holes 3, to make the latter continuous and free from glue runs that would interfere with the reaming operation. 80

85 After the wood sections 1 have been firmly glued together in the clamp 6, with their holes placed in the proper relation to each other and made free from glue runs by the pins 7, the handles are withdrawn from the clamp and reamed, turned and shaped. The holes 3 in the handles thus formed enable the latter to be firmly held in the lathe during the turning operations. These holes are 90 then plugged in their rear ends and left open in their front ends to receive the legs 4, 4 of the tennis racket frame.

95 In Figure 6 I have shown one of the wood sections 1 provided with a bead 8 between the grooves 2, 2, for entrance in a recess 9 in the other section 1 between the grooves 2, 2 therein for the purpose of guiding the grooves in one section into accurate alinement with the grooves in the other section and to assist in firmly holding or locking 100 said sections together after they have been glued.

105 It is now seen that I have not only provided a desirable handle that may be readily and firmly applied to the legs of a metal tennis racket frame, but one which may be produced efficiently and in large quantities by my improved method before described.

110 I do not wish to be limited to the details of construction and arrangement herein

shown and described, and any changes or modifications may be made therein within the scope of the subjoined claims.

Having described my invention, I claim:

- 5 1. The herein described method of making a handle, which consists, first, in cutting two sections from wood, then forming a pair of alined longitudinal grooves, semi-circular in cross section, in a corresponding face 10 of each wood section, then gluing said sections together to bring the grooves in one in alinement with the grooves in the other, and then forcing a heated element into said holes for the purpose specified.

2. The herein described method of making a handle, which consists, first, in cutting two sections from wood, then forming a pair of alined longitudinal grooves, semi-circular in cross-section, in a corresponding face of each wood section, then applying a 20 glue to the grooved faces of said sections and clamping them together, and then forcing pins into the groove-formed holes for the purpose specified.

In testimony whereof I have hereunto set 25 my hand this 2nd day of May, 1922.

HARVEY D. GEYER.
